UNITED STATES PATENT OFFICE.

HOWARD M. WEBSTER, OF CHICAGO, ILLINOIS.

FURNACE-ASHES WASHER.

1,417,645.

Specification of Letters Patent. Patented May 30, 1922.

Application filed March 10, 1921. Serial No. 451,231.

To all whom it may concern:

Be it known that I, HOWARD M. WEBSTER, a citizen of the United States, residing at Chicago, in the county of Cook and State of Illinois, have invented certain new and useful Improvements in Furnace-Ashes Washers, of which the following is a specification.

The object of this invention is to provide a simple, substantial and comparatively inexpensive device or apparatus for household use to conveniently separate furnace ashes into the part which contains partly consumed coal and the part generally fine dust which represents thorough combustion so that the unburned part may be returned to the furnace for further combustion and the other part removed from the furnace room in a compact and moist condition.

Another object of the invention is to provide means for washing furnace ashes which can be filled by shoveling directly from the ash pit and separated without producing the usual cloud of dust which attends the removal of ashes in the ordinary way; and which leaves the incompletely burned part and the completely burned part separated from each other and in a compact condition which permits of easy handling also without producing a dust cloud.

And a further object of the invention is to provide an ash washer which comprises a rotary screen adapted to be easily filled and operated to thoroughly wash the ashes and then adjusted for draining; and finally removed for emptying, to adapt the device in a convenient form for household use, or in larger forms for use in apartment houses or larger buildings.

In the accompanying drawings I have illustrated a selected embodiment of the invention and referring thereto,

Fig. 1 is a sectional view on the line 1—1 of Fig. 2 showing the device in washing position.

Fig. 2 is a sectional view on the line 2—2 of Fig. 1.

Fig. 3 illustrates the screen in draining position.

Fig. 4 shows the screen in filling position.

Referring to drawings, 5 is a tank of suit-

able dimensions adapted to contain a supply of water and provided with a faucet 6 or other suitable drain device which is preferably located slightly below the screen when the latter is in washing position, as shown in Fig. 1. The purpose of this location of the drain is to permit the tank to be filled to its maximum capacity with the separated fine ashes.

A rotary screen 7 is mounted on a shaft 8 which is supported in washing position of the screen in bearings 9 in the cross bars 9' suitably supported on and secured to the tank. In that form of the invention illustrated in the drawings, the screen has a head 10 mounted rigidly on the shaft 8, a head 11 removably mounted on the shaft and a spider 12 rigidly mounted on the shaft within the screen at the end upon which fits the removable head 11. The heads 10 and 11 are preferably of skeleton form and the openings therein are covered with wire mesh corresponding to the wire mesh which forms that portion of the screen between the heads 10 and 11. The two cross bars 9' are preferably located on the tank so that the hubs 10' and 11' of the heads 10 and 11 will fit snugly between said cross bars when the head 11 is properly fitted on the screen so that the screen will be rigidly held with the removable head secured in place thereon against any pressure that may be exerted by the ashes within the screen during the operation of the device. The crank handle 13 is removably engaged with the end of the shaft, 85 being provided with a stud 14 to engage a slot 15 in the shaft or otherwise constructed so that it may be easily and quickly engaged with or disengaged from the shaft. The crank handle is also provided with a socket 16 to engage the shaft 8 and one of the cross bars 10, is provided with a socket 17 so that the crank handle may be utilized for supporting the screen in an inclined position, as shown in Fig. 4 for filling the screen with ashes.

In practice the tank is filled nearly full with water, and the screen is supported by the handle in the tilted position of Fig. 4 for filling. I have found it convenient to re-

move the crank handle from the shaft and then use the end of the shaft as a sort of handle for lifting the screen to the inclined position of Fig. 4. When the screen is lifted 5 sufficiently clear of the tank the head 11 is removed and the crank handle 13 is adjusted to support the screen in the tilted position. Then the ashes are shoveled from the furnace ash pit into the screen. This can 10 be done carefully and without producing a cloud of dust in the furnace room. After the screen has been filled nearly full of ashes the removable head is replaced, the screen returned to horizontal position of Fig. 1 and 15 the crank handle replaced, whereupon the handle is employed to revolve the screen which submerges a considerable portion of the contained ashes in the water. I have found that considerable of the fine ashes will 20 drop through the mesh of the screen into the water when they are shoveled into the screen, and I have also found that the agitation of the ashes created by the revolution of the screen accomplishes a thorough wash- 25 ing of the mass of ashes and a separation of the fine ashes from the part which is only partly or not sufficiently burned so that the latter part can be returned to the furnace for further combustion, thus saving this loss 30 which is many times a material factor due as often perhaps to careless attention to the furnace as to the fault of the furnace itself. After the ashes have been thoroughly washed the screen should be swung to the position 35 shown in Fig. 3 for draining. When the surplus water has drained off of the screen the head 11 is removed from the screen and the contents thereof are dumped upon the furnace floor, or into the coal bin or other 40 convenient place to be returned to the fire box when required. The washed ashes can be used in the ordinary way like coal or they may be used for banking the fire for which they are very satisfactory. When the tank 45 fills with ashes up to the level of the drain it should be emptied and at this time the drain is opened to draw off the water and then the ashes are shoveled out or, if the tank is not too large, the ashes may be dumped 50 out.

My invention is well adapted for household use and it provides a means for conveniently and easily separating and saving the unconsumed ashes which are ordinarily 55 thrown away. My ash washer can be used without producing a cloud of dust and this makes it particularly suited for household use. I am aware that changes in the form and proportion and construction of parts 60 may be made without departing from the invention or sacrificing any of its advantages and I therefore reserve the right to make all such changes as fairly fall within the scope of the following claims.

65 In Fig. 2 I have attempted to illustrate

the condition of the material at the beginning of the washing operation and after the screen has been revolved two or three times. The dust, fine ashes and unburned and partly burned coal in wet condition form a mass 70 which sticks together very much like mud and is carried up by the screen in the manner shown in Fig. 2 and dumped therein upon the surface of the water whereby the fine ashes are separated and washed through 75 the screen and settle to the bottom of the tank.

I claim:

1. Means for washing furnace ashes comprising a water tank, cross bars mounted on the tank, a rotatable shaft supported in bearings on said cross bars and projecting at one end beyond an end of the tank, and a cylindrical screen mounted on the shaft between the cross bars and having heads provided with outwardly projecting hubs to operate in juxtaposition to the bearings whereby to avoid material endwise movement of the screen. 80

2. Means for washing furnace ashes comprising a water tank, cross bars mounted on the tank, a rotatable shaft supported on said cross bars and projecting at one end beyond an end of the tank, a crank handle detachably secured on the projecting end of said shaft, and a cylindrical screen mounted on said shaft between said cross bars and having a removable head at that end adjacent the crank handle, and a fixed head at its other end. 90

3. Means for washing furnace ashes comprising a water tank, cross bars mounted on the tank, half bearings on said cross bars, a rotatable shaft supported in said bearings and projecting at one end beyond an end of the tank, a cylindrical screen mounted on the shaft between said cross bars, said screen having a fixed head at one end and a removable head at the end adjacent said projecting end of the shaft, said heads being located in juxtaposition to said bearings, said projecting end of the shaft providing means whereby the screen may be lifted to tilted position with the removable head end elevated, and a crank handle on said projecting 105 end of the shaft. 110

4. Means for washing furnace ashes comprising a water tank, cross bars mounted on the tank, a rotatable shaft supported on said cross bars and projecting at one end beyond an end of the tank, a screen mounted on said shaft between the cross bars, a crank handle detachably engaged with the projecting ends of the shaft and having a socket in one end to engage the shaft, the cross bar adjacent the projecting end of the shaft having a socket to receive the handle when the latter is engaged therewith to support the screen in tilted position. 120

5. Means for washing furnace ashes com- 130

prising a water tank, cross bars mounted on the tank and having half bearings thereon, a rotatable shaft supported in said bearings and projecting at one end beyond an end of the tank, a cylindrical screen mounted on said shaft between said cross bars, said screen having a rigid head at one end and

a removable head at that end adjacent the projecting end of the shaft, a spider rigidly mounted on the shaft within the screen at that end which is provided with the removable head, and a crank handle on the projecting end of the shaft.

HOWARD M. WEBSTER.
